DESIGN FOR A PENCIL

Martin E. Trolle, St. Paul, Minn., assignor to Brown & Bigelow, St. Paul, Minn., a corporation of Minnesota

Application April 9, 1937, Serial No 68,639

Term of patent 14 years

To all whom it may concern:

Be it known that I, Martin E. Trolle, a citizen of the United States, residing at St. Paul, county of Ramsey, and State of Minnesota, have invented a new, original, and ornamental Design for Pencils, of which the following is a specification, reference being had to the accompanying drawing forming part thereof.

I claim:

The ornamental design for a pencil, as shown.

MARTIN E. TROLLEN.
